UNITED STATES PATENT OFFICE.

DONALD S. BARROWS, OF ROCHESTER, NEW YORK, ASSIGNEE, BY MESNE ASSIGNMENTS, TO THE SYMINGTON COMPANY, A CORPORATION OF MARYLAND.

WEAR PLATE FOR CAR-TRUCK SIDE FRAMES.

Application filed December 17, 1923. Serial No. 681,200.

To all whom it may concern:

Be it known that I, DONALD S. BARROWS, a citizen of the United States, residing at Rochester, in the county of Monroe and State of New York, have invented certain new and useful Improvements in Wear Plates for Car-Truck Side Frames; and I do hereby declare the following to be a full, clear, and exact description of the invention, such as will enable others skilled in the art to which it appertains to make and use the same.

This invention relates generally to car truck side frames, but more particularly stated involves the production of a very strong and durable wear plate adapted to be connected to the truck columns for receiving the wear incident to the movement of the bolster.

The principal object of the invention resides in the production of wear pads from the material salvaged from the blanks used in the construction of wrought metal car truck side frames, said material being first blanked and then subjected to one or more forging operations wherein the portions of the plate through which the rivets pass are offset from the body portion of the plate to provide very convenient projections which, in addition to being readily positioned against the truck columns, are also recessed to permit of the heads of the rivets being countersunk beneath the wearing surfaces of the plate.

Another object of the invention is to provide a construction of side frame and bolster wear pad in which the truck column and stiffening flanges bordering the same are embraced by the pad, the offset portions of said pad coacting with the inturned stiffening flanges in providing a comparatively simple but exceedingly strong construction in which the openings receiving the rivets can be punched, thereby obviating the expense incident to the employing of special drilling equipment. Other advantages, such as the providing of ample space for entering, bucking and driving the rivets follows from my present construction of wear pad and flanged truck columns, the simple bevel of the flanges requiring less working and resulting stretching of the metal, and also improving the appearance of the side frame.

With these and other objects in view, the invention further consists in the construc-

tion, arrangement and combination of the several parts, as well as the method of manufacturing the wear plates, all as will be more fully hereinafter described.

In the drawings illustrating the invention, the scope whereof is pointed out in the claims:

Figure 1 is a side view of a fragmentary portion of a car truck side frame showing my improved wear plates applied to the truck columns thereof.

Figure 2 is a view of the wear plate blank cut from the material salvaged from the blank or blanks used in construction of a wrought metal car truck, the salvaged material being indicated by the dot and dash lines.

Figure 3 is a perspective view of the wear plate blank as shaped by the initial forging or bending operation.

Figure 4 is a face view of the completed wear plate.

Figure 5 is a horizontal sectional view on the line 5—5 of Figure 4 through the wear plate, and showing the same connected to the truck column portions of the wrought metal side frame.

Referring to the drawings in which similar reference characters designate corresponding parts in the several views, the numeral 1 indicates a car truck side frame formed from a sheet metal blank or blanks in which the inner and outer side walls may each be formed with a plurality of top arch bar portions, a plurality of bottom arch bar portions and a plurality of truck column portions. The truck column portions 2 are each formed with an inwardly extending flange 3 along their outer edges and an inwardly extending flange 4 along their inner edges, said last named flange forming a beveled portion bordering the upper part of the truck columns and being adapted to have connected thereto the wear plate 5.

The inturned flanges receiving the wear plates are each disposed so as to form a beveled portion bordering the bolster opening, the angle of which beveled portion is less than a right angle with respect to the adjacent side wall. The lowermost portions of the stiffening flanges 4 are preferably inturned at right angles to the respective side walls, the metal at the junction of the beveled portions and right angularly disposed portions of the flanges being bent so as to

effect a gradual easement thereof without stretching or otherwise impairing the strength value of the column. As a result of this construction the truck column stiffening flanges bordering the bolster opening can be easily bent in the manufacture of the side frame.

The wear plate 5 is preferably formed from the scrap pieces of the blank or blanks 10 cut from the side walls in the formation of the several side frame portions, said pieces being cut to provide the rectangular blanks 6 from which the wear plate is produced. The blank 6 is first bent to form the flanges 15 7 and then subjected to a drop forging operation which, in addition to reshaping said flanges, also forms the projections 8. The projections 8 are pressed from the body web portion of the plate away from the wearing 20 surface thereof so as to provide recesses 10 into which the heads of the attaching rivets are received, said projections being disposed in offset relation to the wearing surface, but preferably normally disposed in upright 25 planes. The projections 8 are arranged at an angle to the body web portion corresponding to the angular disposition of the upper portions of the stiffening flanges 4. The metal forming the projections 8 is 30 partly forged from the flanges 7, the recesses receiving the rivets intersecting the bearing areas provided on said flanges adjacent the wearing surface of the body web.

Each projection 8 is provided with an 35 opening 9 adapted to receive an attaching rivet 11, said rivet being further inserted into a registering opening formed in the adjacent stiffening flange of the truck column. The rivets are disposed at right angles to 40 the planes of junction of the projections and stiffening flanges thereby readily facilitating the insertion and heading of the rivet in providing a very strong and rigid connection of the wear plate to the truck column.

A bolster wear plate constructed in accordance with the present invention provides for an increased side bearing area and at the same time permits of the use of rivets which 50 can be economically applied and properly headed without impairing the wearing surfaces of the plate.

The method of manufacturing my wear plate consists in cutting a rectangular metal blank to the desired size, then flanging said blank by bending opposite side edge portions thereof, as shown in Figure 3. The flanged blank is now subjected to one or more forging operations in which the body web portion 55 of the plate and an adjacent flange is shaped to provide an offset projection or attaching portion.

The metal of the plate is offset at the junction of the wearing surface of the body web and the side bearing area of the adja-

cent flange, said offset, in addition to providing the projections 8, also forming a recess for housing the head of the attaching means in countersunk relation to said wearing surface and adjacent side bearing area. 70

I claim:

1. A wear plate adapted to be connected to the truck column of a car truck side frame, said plate involving a body web having a wearing surface, flanges extending 75 from said body web and providing side bearing areas adjacent the wearing surface, and attaching projections extending from the plate, said projections being formed by offsetting adjacent portions of the body web 80 and flanges.

2. A wear plate adapted to be riveted to the truck column of a car truck side frame, said plate involving a body web having a wearing surface, and attaching portions 85 formed by offsetting the body web into upright planes angularly disposed with respect to the web, the offsetting of said body web providing recesses adapted to receive the heads of the rivets in countersunk relation 90 to said wearing surface.

3. A wear plate for car truck side frames comprising a body web having a wearing surface, flanges extending from said body web and providing side bearing areas adjacent the wearing surface, and projections extending from said body web in offset relation 95 thereto, said projections being recessed for receiving the means connecting the wear plate to an adjacent portion of the side frame 100 in countersunk relation to said wearing surface and bearing areas of the plate.

4. A wear plate for car truck side frames comprising a body web having a wearing surface, and attaching portions formed by 105 offsetting said body web at spaced intervals to provide projections, each of said projections having an attaching face disposed in a substantially upright plane at an angle to the wearing surface and being provided 110 with an opening adapted to receive the means connecting the plate to an adjacent portion of the side frame.

5. A flanged wear plate for car truck side frames comprising a body web having a 115 wearing surface and flanges providing side bearing areas, projections provided on said plate and disposed at an angle to the wearing surface and bearing areas, said projections being formed by depressing the body 120 web and flanges, thereby providing recesses adapted to house the means connecting the plate to the side frame.

6. A wear plate for car truck side frames comprising a body web having a wearing 125 surface, and attaching portions in upright planes angularly disposed with respect to said wearing surface and arranged in offset countersunk relation thereto, each of said attaching portions being provided with an 130

opening the axis of which is arranged at right angles to the angular disposition of the attaching portion.

7. A wear plate of the class described having a plurality of wearing surfaces, and attaching projections for connecting the plate to an adjacent portion of the side frame, said projections being formed by offsetting portions of the plate at the intersection of adjacent wearing surfaces, each of said projections being provided with an opening adapted to receive a rivet.
10. The combination with a car truck side frame having truck columns and stiffening flanges therefor, of a bolster wear plate provided with portions adapted to be connected to said columns, said portions being offset from the plate and disposed at an angle corresponding to the angular disposition of the stiffening flange with respect to the adjacent truck column.

15. The combination with a car truck side frame having truck columns and stiffening flanges therefor, each of said flanges being disposed at an angle to the columns which is less than a right angle, a wear plate having a projecting portion offset therefrom, said projection being disposed at an angle corresponding to the angular disposition of the 20 stiffening flange, and means connecting said projecting portion to said flange.
25. In combination, a car truck side frame having inner and outer side walls, each of said walls having a bolster opening and a plurality of truck column portions, stiffening flanges for said columns each having a portion bordering the bolster opening, which portion is disposed at less than a right angle to the adjacent side wall, a bolster wear

plate having portions thereof offset to provide projections, each of said projections being disposed at an angle corresponding to the said angular disposition of the stiffening flange portion, and means including a rivet for connecting the plate to the stiffening flange, said rivet being adapted to pass through a projection of the wear plate and an adjacent portion of the stiffening flange at right angles to the angular arrangement of said parts.

30. The method of forming a bolster wear plate for car truck side frames which consists in flanging a flat metal blank, and then subjecting said flanged blank to one or more forging operations to form attaching portions, said attaching portions being formed by offsetting the plate at the junction of the flange with the body web.

35. The method of forming a bolster wear plate for car truck side frames which consists in flanging a flat metal blank, and then subjecting said flanged blank to one or more forging operations to form attaching portions, the said attaching portions being formed by offsetting the portions of the body 40 and having provided therein an opening disposed at an angle to the face of said body web.

45. A wear plate for car truck side frames comprising a body web having a wearing surface and an attaching portion offset with relation to said wearing surface, said attaching portion being provided with an opening the axis of which is disposed at an angle to the wearing face of the body web 50 and in a substantially horizontal plane.

In testimony whereof I affix my signature.
DONALD S. BARROWS.
